UNITED STATES PATENT OFFICE

2,515,828

METHOD AND APPARATUS FOR FINISHING
FABRIC ARTICLESEdwin Roper Jarman, London, Ontario, Canada,
assignor to E. R. Jarman & Co. Limited, Lon-
don, Ontario, CanadaApplication December 1, 1945, Serial No. 632,169
In Canada November 12, 1945

13 Claims. (Cl. 223—70)

1

This invention relates to a method and apparatus for finishing garments and other fabric articles after cleaning of the same.

It is recent practice, in garment cleaning establishments, to finish a cleaned article by placing it on an inflatable but permeable form or dummy, steaming the article by forcing steam through the form, and finally drying the article by forcing heated air through the form, the latter being maintained in distended and article-engaging position under the action of the steam and air. The "dressing" and "undressing" of a substantially full form or dummy is a time-consuming operation, but it has heretofore been considered advisable to ensure distention of the garment under treatment by causing the inflated form to engage substantially the entire inside surface of the garment.

It is an object of the present invention to provide a method and apparatus for finishing articles by subjecting them to the action of steam and hot air in a more rapid, convenient and effective manner than has heretofore been considered possible. It is another object to provide a device of the type referred to which is of simplified and inexpensive construction.

Other objects, details and advantages of the invention will be apparent from the following description with particular reference to the accompanying drawings in which

Figure 1 is a front elevation of a device constructed in accordance with the invention,

Figure 2 is a side elevation,

Figure 3 is an enlarged sectional plan view of a portion of the device, certain parts being broken away or omitted for clarity of illustration,

Figure 4 is an enlarged sectional front elevation,

Figure 5 is an enlarged plan view of one of the steaming cones of the device,

Figure 6 is a front elevation of a garment hanger,

Figure 7 is a sectional side elevation of the garment hanger,

Figure 8 is a sectional elevation of a steam nozzle,

Figure 9 is a plan view of the steam nozzle,

Figure 10 is a front elevation of a skirt or like hanger, and

Figure 11 is an end elevation of the skirt or like hanger.

Referring to the drawings, the device comprises one or, preferably, two steam and air distributing units 1, an air heater and blower unit 2, and a garment hanger 3 for suspending a garment or the like over each unit 1.

2

Each unit 1 comprises an upright cylinder 4 forming a cylindrical plenum chamber 4' having a steam nozzle 5 therein supplied with steam from the pipe 6 and an inlet 7 communicating with a passage 8 formed by the walls 9 and leading to the unit 2. The cylinder 4 is open at the top and is provided with an upwardly extending tripod supporting frame 10, the legs of which are secured to the cylinder adjacent the top thereof. Supported on the tripod frame is a substantially frusto-conical fabric cover 11, formed of a permeable cotton or like material. A drawstring 12 may be provided at the lower edge of the fabric cover to enable the same to be secured in tightly engaging relation with the top portion of the cylinder. A drawstring 13 may also be provided at the upper edge of the fabric cover to form a means for adjusting the size of an opening 14 in the top portion of the cover or for closing such opening.

The air heating and blower unit 2 is of usual construction and includes a casing 19, a steam heating coil or the like 15 for heating the incoming air, and a blower wheel 16 driven by a motor 17 for blowing the heated air into the passage 8.

The article hanger 3 comprises an upright post 18, which may conveniently be fixed to the casing 19, having a forwardly extending upper portion or arm 20, at the end of which is fixed a sleeve 21 in axial alignment with the chamber 4' and conical fabric cover 11. A rod 22 is slidably mounted in the sleeve and means are provided for locking the rod in any desired position and for permitting ready adjustment of such position. Such means may comprise a washer 23 carried by an angularly extending manually depressible plate 24 which is pivoted to an arm 25 on the sleeve. The rod extends through the washer and is adapted to be pinched thereby when the latter is in inclined position as shown. A spring 26 acting on the arm 25 normally maintains the washer in rod locking position.

At the lower end of the rod is a swivelly mounted block 27 on which is fixed a substantially triangular bib 28. The bib 28 may be formed of canvas or like material and has a stiffening rib 29 formed of spring steel seated in a centrally disposed pocket 30 provided on the rear surface of the bib. The edges of the bib may be reinforced and stiffened by means of tape 31 or the like. The rib extends in a downward and outwardly inclined direction from the block 27 and is generally convex in transverse section. A pin 32 is mounted in the upper rear portion of the block 27. As shown in Figures 1 and 2, a garment 33 on an ordinary

hanger 34 is adapted to be placed on the hanger assembly 3 without removing the ordinary hanger 34 which is held in position by the stop pin 32. The bib 28 is adapted to substantially fill the neck opening of the garment, the bib being of such size that it will fill neck openings of a wide range of sizes.

In operation, the garment on its usual hanger is simply hung on the assembly 3, as described, and the neck portion of the garment adjusted around the bib. The hanger rod 22 is then adjusted to place the lower edge or hemline of the garment in slightly spaced or in delicately contacting relation with the conical cover 11 of the unit 1. Steam is then admitted to the plenum chamber 4' through the nozzle 5 and flows upwardly into and through the conical fabric cover 11 which effectively distributes it into the suspended garment. After the steaming operation, heated air is blown through the garment to dry the same.

It is to be particularly noted that substantially the entire garment is free from contact with the steam and air distributing cone 11. Thus, garments are free to assume their normal shape under the influence of the steam or air under pressure, with substantially no possibility of stretching as may occur when a contacting distendable bag is employed. Moreover, staining or spotting of the garment by water slugs, which frequently occur when there is contact between the garment and distributing means, is substantially eliminated.

The absence of a full form or dummy, which has to be virtually dressed and undressed each time a garment is processed, drastically cuts the time required for application and removal.

Moreover, since in most plants garments enter for finishing on the usual wire or wood hangers, much time is saved by permitting the original hanger to remain in the garment during finishing. Elimination of this tedious time-consuming operation of removing and replacing hangers is of great importance from a production cost standpoint.

Since the hanger supporting block 27 is swivelly mounted, the garment may be readily rotated to permit inspection during the finishing operation.

An important feature of the invention resides in the provision of a pair of garment treating devices combined in a single finishing machine, as shown in Figures 1 to 4. For this purpose, the passage 8 is Y-shaped to form two outlet branches 35 and 36 leading to the respective plenum chambers 4'. A continuation 36' of the steam supply pipe 6 communicates with the steam nozzle 5 of the second plenum chamber 4', and pipe 37 from the second nozzle leads to a return trap.

Each steam nozzle is provided with a normally closed valve 38, and means for opening each valve comprises a lever 39 pivotally supported on the valve body at 40 and having one end adapted to contact the valve actuating plunger 41 and its other end pivoted to a link 42. The link 42 extends through the wall of cylinder 4 and is pivoted to one end of a bell-crank lever 43 which is pivotally mounted in a bracket 44 fixed to the outer wall of the cylinder. A link 45 pivotally connects the other end of lever 43 with an operating pedal arm 46, the inner end of which is loosely pivoted on a pin 47 mounted in a frame member 48 and the outer end of which extends through an opening 49 in a frame member 50. Such outer end carries the foot-engaging plate 51. The opening

49 is of a height to permit sufficient vertical rocking movement of the pedal arm to actuate levers 39 and 43 through the intermediate links 42 and 45 to open the valve 38, as shown on the left hand side of Figure 4, or to allow the valve to close under the action of a spring 52 connected to lever 43 and a frame member 53, as shown on the right hand side of Figure 4. A laterally extending slot 54 is provided at the lower portion of opening 49 to receive and hold the pedal arm in valve-opening position.

Means for controlling the flow of air in the passage portions 35 and 36 comprises an air damper 55 adapted in one position to close portion 35 and open 36 and in its other position to close portion 36 and open 35. The damper 55 is fixed to a rod 56 rotatably mounted in bearings 58. An arm 58' for rotating rod 56 and imparting swinging movement to the damper is fixed to the rod and is provided with a vertically extending portion 59. Means for actuating the arm 58' comprises a shaft 60 journalled in frame parts 50 and 61, an upwardly extending bar 62 fixed to the inner end of the shaft and having a U-shaped portion or yoke 63 on its upper end in engagement with the vertically extending portion 59 of the arm 58', and a bi-pedal arm 64 fixed to the outer end of the shaft for imparting rotative movement to the shaft. It will be observed that when the bi-pedal arm is rocked in one direction, the U-shaped portion 63 will swing laterally carrying with it the part 59 of arm 58' and thus swing the latter to move the air damper into engagement with the wall of one of passage portions 35 and 36, as shown in Figure 3.

Means for ensuring that the air passage and steam valve of any other chamber 4' will not be open at the same time comprises a T-shaped lever 65 pivoted to the frame member 48 at a point between the pedal arms 46 and having the extremities of its cross arm 66 located to engage either pedal arm 46 when positioned in the catch or slot 54. The arm 58' of the air damper passes through a notch 67 in the cross arm 66 whereby the side to side movement of the arm 58' will also impart side to side movement of the lever 65 about its pivot and cause the cross arm extremity to engage and push the respective pedal arm 46 out of its catch 54, thus permitting automatic closing of the steam valve under the action of spring 52. Fine adjustment of the length of the cross arm 66 is provided by means of screws 68 mounted in the ends thereof.

Figures 8 and 9 illustrate in detail the improved type of steam nozzle which it is proposed to employ and which is adapted to satisfactorily diffuse the steam while at the same time efficiently separating therefrom any drops of moisture which might cause spotting of garments. The nozzle comprises a substantially cylindrical member 69, preferably formed of brass, and adapted to be attached to the valve 38. A cylindrical chamber 70 having a conical top portion 71 is formed with the member 69. The outer top surface 72 of the member is also substantially conical and a plurality of steam jet holes 73 extend from the portion 71 to the surface 72. A horizontally disposed steam diffuser disc 74 surmounts the member 69 whereby steam jets issuing from the holes 73 will impinge on the lower surface of the disc and be outwardly diffused thereby. Any drops of moisture in the steam will be deflected by the disc and fall into the bottom of the plenum chamber where the hot air, during subsequent drying, gradually evaporates them. The use of such a

nozzle, situated as it is below the rim of the plenum chamber, eliminates the necessity for any moisture separator in the steam supply line or for any fabric or other type of shield over the steaming outlet. Because of the absence of such a separator or shield, a very rapid steaming action is obtained without danger of spotting garments with water drops.

Figures 10 and 11 illustrate a modified and adjustable form of garment hanger assembly adapted to support a garment, such as a skirt, which is not susceptible to hanging on the usual type of hanger. As shown, a cross arm 75 is mounted on the lower end of the hanger rod 22 and a pair of slides 76, one on each end portion of the cross arm, are freely slidable thereon. Each slide carries a depending garment-engaging finger 77, which may be rubber covered to improve the gripping action on the garment. A weight 78 is slidably mounted on the rod 22 and is pivotally connected by links 79 with the slides 76. A pin 80 limits the downward movement of the weight. It will be observed that upward movement of the weight 78 will cause inward movement of the two slides whereby a garment, such as indicated at 81, may be positioned in relation to the fingers 77 as shown. Thereafter the weight is permitted to move downwardly to cause outward movement of the slides and gripping engagement of the fingers with the garment while at the same time closing the top opening of the garment. A needle 82 on one of the fingers 77 may be provided to hold the slit or placket of skirts and the like closed during the finishing operation.

The employment of a two-garment handling machine results in a particularly efficient and rapid treatment of garments. While the first garment is being steamed on one side the operator can be removing a finished garment from the other side and placing a third one ready for steaming. Since steaming time is only about 10 seconds, the first garment is ready to be subjected to hot air drying about the time the operator has the third garment placed. Stepping on the air pedal, of course, automatically discontinues the steaming of the first garment, and the steaming of the third garment can then be proceeded with.

The hot air blower fan is adapted to run continuously while the machine is in use. A very minute amount of air will flow past the closed air damper 55 due to unavoidable tolerances in the fit thereof. However, this minute quantity of air under pressure has a favourable effect in the steaming operation since it acts to force the steam downwardly into the sleeves of the garment under treatment.

It has been found desirable to bleed a small amount of air into the plenum chamber over which a garment is being replaced. The purpose of this air is to prevent the skirt of the garment from touching, binding or catching on the fabric cone and thus ensure rapid and convenient placing of the garment in position. The aforementioned minute quantity of air which flows past the closed air damper is not sufficient for this purpose and it is therefore proposed to provide automatic means for bleeding an effective quantity of air for this purpose. Referring to Figure 3, an upright pin 83 is fixed to each steam-controlling pedal arm 46 to provide a stop which, when the pedal arm is in its upper or valve-closed position, serves to prevent the air damper 55 from reaching fully closed position, as shown

in dotted lines. The pin 83 is of limited height so that, when the pedal arm 46 is depressed to open the steam valve, it is drawn out of engagement with the air damper to release the latter and permit the air pressure from the fan to close the remaining opening and thereby stop the air bleeding. The presence of the amount of air provided by the air bleeding described would be detrimental during the steaming operation.

It will be understood that various changes may be made in the structural details described without departing from the spirit of the invention.

What is claimed is:

1. A fabric article finishing machine comprising a steam and hot air receiving container, a permeable fabric hood mounted on the container and receiving steam and hot air therefrom, an article hanger suspended above the hood in spaced vertical alignment therewith, and means for supporting said hanger comprising a post having an overhanging portion, and a substantially vertically disposed rod slidably carried by said overhanging portion for perpendicular adjustment, a device for locking the rod in adjusted position, and a member swivelly carried by the lower end of said rod and adapted to carry said hanger.
2. A fabric article finishing machine as defined in claim 1, wherein said hanger comprises a block swivelly carried by said rod, and a substantially triangular fabric bib fixed to the block and extending in a downward and outwardly inclined direction therefrom, said bib having stiffening means incorporated therein.
3. A fabric garment finishing machine comprising a steam and hot air receiving container, a substantially conical permeable fabric hood mounted on the container and receiving steam and hot air therefrom, and a garment hanger suspended over the hood in spaced vertical alignment therewith, said hanger including a supporting post, a vertically adjustable rod carried by the post, a member swivelly carried by the rod, and a substantially triangular bib carried by the member and adapted to fill the neck opening of a suspended garment, the space between said bib and hood being free from intervening bodies other than a suspended garment.
4. A fabric garment finishing machine comprising a steam and hot air receiving container, a substantially conical permeable fabric hood mounted on the container and receiving steam and hot air therefrom, and a garment hanger suspended over the hood in spaced vertical alignment therewith, said hanger including a vertically disposed and perpendicularly adjustable rod, a bar fixed to the end of the rod at right angles thereto, a pair of slides on the bar and having garment engaging fingers depending therefrom, a weight slidably on the rod, and links pivotally connecting the weight and slides.
5. A fabric article finishing machine comprising an open top container, means for supplying hot air to the container, a steam nozzle in the container comprising a housing for receiving steam having a plurality of steam outlets in the top thereof and a plate spaced above the housing and on which the steam jets issuing from the outlets are adapted to impinge, a permeable fabric hood mounted on the top of the container and receiving steam and hot air therefrom, and an article hanger suspended over the hood in spaced vertical alignment therewith.
6. A fabric article finishing machine comprising

ing an open top container, means for supplying hot air to the container, a steam nozzle in the container comprising an upright cylindrical housing for receiving steam, the inner and outer top surfaces of the housing being substantially conical, the top of the housing having a plurality of inclined steam outlet openings therein extending from the inner to the outer conical surface, and a substantially horizontally disposed disc spaced above said openings and on which the steam jets issuing from said openings are adapted to impinge, a permeable fabric hood mounted on the top of the container and receiving steam and hot air therefrom, and an article hanger suspended over the hood in spaced vertical alignment therewith.

7. A fabric article finishing machine comprising a pair of article treating devices each including an open top container, a permeable fabric hood mounted on the top of the container, and an article hanger suspended over the hood in spaced vertical alignment therewith, a steam supply pipe communicating with each container, a valve in each pipe within the container for controlling the steam supply, a hot air supplying unit, means forming a hot air passage leading from the unit and having branches communicating with each container, a valve for closing either of said branch passages, and manually actuatable means for controlling said steam and air valves.

8. A fabric article finishing machine comprising a pair of article treating devices each including an open top container, a substantially conical permeable fabric hood mounted on the top of the container, and an article hanger suspended over the hood in spaced vertical alignment therewith, a steam supply pipe communicating with each container, a valve in each pipe within the container for controlling the steam supply, a manually actuatable lever for opening and closing each valve, a hot air supplying unit, means forming a hot air passage leading from the unit and having branches communicating with each container, a damper for closing one of the branch passages while opening the other, manually operative means for actuating said air damper, and means responsive to actuation of said air damper for closing one of said steam valves.

9. A fabric article finishing machine comprising a pair of article treating devices each including an open top container, a permeable fabric hood mounted on the top of the container, and an article hanger suspended over the hood in spaced vertical alignment therewith, a steam supply pipe communicating with each container, a valve in each pipe for controlling the steam supply, a hot air supplying unit, a lever for opening and closing each valve, a pedal for actuating each lever, means forming a hot air passage leading from the unit and having branches communicating with each container, an air damper for closing one of the branch passages while opening the other, a lever for actuating the air damper, and a bi-pedal for operating the lever.

10. A fabric article finishing machine as de-

fined in claim 9 including a lever actuatable by movement of said air damper actuating lever for actuating said steam supply controlling pedal to close the valve controlled thereby.

5 11. A fabric article finishing machine comprising a plurality of article treating devices each including an open top container, a permeable fabric hood mounted on the top of the container, a steam supply pipe communicating with each container, a hot air supplying unit, means forming a hot air passage leading from the unit and having branches communicating with each container, and means for controlling the flow of steam through said pipe and for controlling the flow of hot air through each of said branches.

12. A fabric article finishing machine comprising a plurality of article treating devices each including an open top container, a permeable fabric hood mounted on the top of the container, and article hanging means suspended over the hood in spaced vertical alignment therewith, a steam supply pipe communicating with each container, valve means in each pipe within the container for controlling the steam supply, a hot air supplying unit, means forming hot air passages leading from the unit and communicating with each container, valve means for interrupting communication between each container and a hot air passage, and means for controlling the steam and hot air valve means.

13. A method of finishing a fabric garment which comprises freely suspending the garment on a conventional coat hanger and, while maintaining the opposing inner surfaces of the garment throughout the major length of the garment free from the presence of intervening solid bodies and the entire portion of the garment other than the hanger-engaging portion in free and unattached relation, successively admitting steam and heated air under pressure to the interior of the garment at points between the lower portions of said inner surfaces, the garment being free to distend to its normal shape under the influence of said steam and heated air.
